AIR VENTING VALVE FOR USE WITH HOT WATER RADIATORS

Warren T. Ferguson, Newton Highlands, Mass., assignor to Anderson Products, Incorporated, Cambridge, Mass., a corporation of Massachusetts

Application October 8, 1953, Serial No. 384,866

6 Claims. (Cl. 137—197)

This invention is particularly concerned with an air vent which may be used in connection with a hot water heating system to vent quickly the air in each individual radiator at the beginning of the heating season and which will function thereafter to vent slowly such air as may accumulate in each radiator as the heating season progresses.

The conventional practice up to the present in hot water heating systems of the type commonly used in homes is to provide a small key operated valve located near the top of each radiator. At the beginning of each heating season, the system should be filled with water. The trapped air in the top of each radiator is permitted to escape by opening the key operated valve. After the radiator is filled with water and the air expelled, the valve is closed. Thereafter, as the system functions, air that is present in the water gradually escapes therefrom to accumulate anew in the top of each radiator. In so doing, the water level in each radiator falls and the heating efficiency correspondingly declines.

There is, however, ordinarily available in a separate tank connected to the system, additional water under pressure so that the water level in each radiator may be restored as soon as the air in the top of each radiator is vented therefrom. To restore the water level under the previous practice has required manual opening of each radiator valve which operation is usually not attended to with proper regularity. Accordingly, under ordinary existing conditions it has been found that, in general, the heating efficiency tends to decline as the heating season progresses.

Therefore, it is an object of the present invention to provide a valve of such character and construction that it may be substituted for the present key actuated valve to permit the immediate and continuous escape from the radiator of any air that collects in the upper portion. This assumes of course that there is a suitable supply of water under adequate pressure to raise the level in the radiator and to expell the gas through the automatically operating valve.

The valve of the present invention in addition to its automatic air venting feature is designed to permit quick venting by manual actuation at any time. Ordinarily, this quick venting operation will occur only at the beginning of each season. Thereafter, the venting will be automatic as the water level is raised.

The invention further includes a construction which while permitting the slow continuous escape of air will automatically seal itself against the escape of water when the water reaches the valve level.

A further object of this invention is the provision of a construction permitting low cost assembly of the various parts making provision at the same time for an entrance port of small size so that the amount of water in the form of condensate or otherwise that may collect in the entrance port will be limited, thereby facilitating proper venting on each venting cycle.

These and other objects of the invention will become

2

more apparent as the description proceeds with the aid of the accompanying drawings in which:

Fig. 1 is a vertical cross-sectional view of the valve screwed in position in the wall of a radiator.

Fig. 2 is a section on the line 2—2 of Fig. 1.

Fig. 3 is a section on the line 3—3 of Fig. 1.

Referring to the drawings, a section of the wall of a radiator 2 is shown with the customary threaded hole 4 into which has been screwed the valve of the present invention generally indicated at 6. This valve consists of a body 8 threaded at 10 to be received by threads 4. The body is enlarged at 12 to provide a hexagonal exterior formation 14 permitting it to be gripped readily by a wrench or other tool. The body 8 has an interior longitudinal bore 16 of relatively large substantially uniform diameter which terminates at the shoulder 18. Extending from the inner edge of shoulder 18 to the right hand end of the body 8 is a passage 20. A head 22 with an outer flange 23 has a shank 24 extending therefrom which shank terminates at shoulder 26 to engage with the right hand end of body 8. A tubular extension 28 extends through passage 20 fitting closely therein and has its end riveted over as at 30 to engage against shoulder 18 and thereby to secure the head 22 firmly on the end of body 8.

Surrounding shank 24 and located between the end of body 8 and flange 23 are a plurality of hydroscopic annular disks 32 which have a small amount of clearance with shank 24 and which when dry will not completely fill the space between body 8 and flange 23.

The passage through extension 28 and into shank 24 is numbered 34. This passage connects with a hole 36 leading to the interior of the disks 32.

A hole 38 bored through one of the hexagonal sides 35 14 leads from the exterior thereof to the interior of bore 16. This hole is threaded as shown to receive a quick venting screw 40 which is milled flat on one side as at 42 and bent over as at 44 on its inner end to prevent its removal. A washer 46 is positioned between the head 40 and body 8 to prevent leakage when the screw is set up tight.

In bore 16 is positioned a short tubular element 48 having a small bore 50 therethrough. This tube is staked in position as at 52.

In assembling the above described unit, the disks 32 are first positioned over shank 24. Extension 28 is then pushed through bore 20 and the end riveted over as at 30 by a tool inserted into bore 16. Screw 40 with washer 46 thereon is then inserted into the threaded hole 38 and after being set up tight, is backed off a limited amount. Then, a tool is inserted through bore 16 to exert sufficient force against the end of screw 40 to bend it as at 44. Screw 40 is then set up tight again after which tube 48 is placed in bore 16 and secured by staking it as at 52. The valve is then complete and ready for operation.

The operation of the valve is as follows: It is first screwed into the radiator to the position shown. As the water level may rise in the radiator, air will be forced through bore 50, passage 34, hole 36 and out to the atmosphere past the sides of disks 32. If it is desired to permit the air to escape more rapidly, screw 40 can be backed off until washer 46 is no longer in sealing engagement with the head of screw 40. Air can then escape easily through bore 50 and out through hole 38 past the flat side 42 of screw 40.

In due course the water level will rise in the radiator and water will enter bore 50, traveling along to passage 34 and out through hole 36. On reaching hydroscopic disks 32, the water causes them to swell to increase their thickness so that they form a tight compact mass between the interior of head 22 and the end of body 8. The pressure developed by the disks against each other as they

swell from the initial water received therein is such that they act as an effective seal against the escape of the following water.

From the foregoing explanation it will be seen that the valve functions automatically to permit the escape of air whenever the pressure in the radiator is greater than the surrounding atmospheric pressure. Pressure above atmospheric may be caused by a rising water level in the radiator or by escape of gas from the radiator water. Upon rise of the water level to the valve, escape of water is prevented by the automatic swelling of disks 32. Thereafter, as the water level in the radiator recedes, the disks 32 will dry out putting themselves in condition for further venting of air whenever the pressure again increases above atmospheric.

It should be noticed that disks 32 are exposed to the atmosphere about their entire peripheries. This is of considerable advantage as it facilitates rapid drying of the disks after the water recedes and it has the additional advantage of minimizing the cost of construction of this type of valve. The tube 48 inserted after screw 40 has been bent at its inner end is designed to minimize the amount of condensate or water which will remain in bore 50. In other words, as the water level in the radiator falls, a limited amount of water or condensate will remain in bore 50, in the cavity around the inner end of screw 40 and in the passages 34 and 36. If tube 48 with its small bore 50 were not present, the amount of water to be evaporated through disks 32 would be considerably greater, in which latter case, the venting of air from the radiator would be correspondingly delayed.

From this explanation it can be seen that the insertable tube 48 provides a desirable construction that facilitates valve operation. Tube 48 may be supplied economically by utilizing a piece of standard tubing, thus eliminating the necessity of boring out the hole 50.

It is my intention to cover all changes and modifications of the example of the invention herein chosen for purposes of the disclosure which do not constitute departures from the spirit and scope of the invention.

I claim:

1. An air venting valve comprising a valve body having a threaded portion at one end for screw threaded engagement with a radiator, a passage through said body, a shank fixed with respect to and extending from said body, a flange on the end of said shank and spaced from the end of said body, a plurality of hygroscopic elements mounted on said shank between said body and flange and another passage through said shank leading from said body passage to the interior of said hygroscopic elements, the combined thicknesses of said hygroscopic elements when dry being such that air reaching said elements through said passages may pass thereby to the atmosphere, but when said elements are moistened by water coming through said passages, said elements will expand

55

and press with sufficient force against the end of said body and said flange to substantially stop further flow of water through said passages.

2. An air venting valve as set forth in claim 1, said body passage being of reduced diameter toward the exit end, thereby to form an interior shoulder, said shank having a tubular extension extending into said body passage, the end of said extension being flared outwardly to make engagement with a shoulder in said body passage.

3. An air venting valve as set forth in claim 1, said hygroscopic elements being completely unenclosed about their entire perimeters.

15 4. An air venting valve as set forth in claim 1, said body passage being formed in part by a length of tubing positioned in a larger bore to provide a fluid opening of much less capacity than the said bore in which said tubing is placed and a quick venting valve comprising a screw positioned in a threaded opening leading from said body passage through the wall of said body, said larger bore being of sufficient diameter to permit the insertion, when said tubing is not positioned therein, of a tool adapted to engage and bend the inner end of said screw to prevent the subsequent removal of said screw from said body.

5. An air venting valve comprising a body having a threaded end adapted to be screwed into a radiator, a passage through said body, a head comprising a flange and a shank, said shank being secured both to said body and said flange, a plurality of hygroscopic disks surrounding said shank and positioned between the end of said body and said flange with their perimeters entirely exposed and a passage through said shank leading to the interior perimeter of said hygroscopic disks whereby water reaching said disks will cause expansion of said disks sufficient to bring said disks into tight engagement with said body and flange to stop further flow of water through said passages.

6. An air venting valve as set forth in claim 1, said body passage being of reduced diameter toward its exit end, thereby to form an interior shoulder, said shank having a tubular extension extending into said body passage, the end of said extension being flared outwardly to make engagement with said shoulder in said body passage, said body passage being formed in part by a short tube positioned within a larger bore in said valve body, said larger bore being of a sufficient diameter to permit the insertion of a tool for flaring the said end of said extension prior to the insertion of said tube.
